(57) **CLAIM**

I claim the ornamental design for a pocket, as shown and described.

DESCRIPTION

FIG. 1 is a perspective view of a pocket showing my new design having a hook-and-loop type fastener and in the closed position;

FIG. 2 is a front elevational view thereof, illustrated in an open position;

FIG. 3 is a rear elevational view thereof, illustrated in the open position;

FIG. 4 is a right-side elevational view thereof, illustrated in the open position;

FIG. 5 is a left-side elevational view thereof, illustrated in the open position;

FIG. 6 is a top plan view thereof, illustrated in the open position; and,

FIG. 7 is a bottom plan view thereof, illustrated in the open position.

The broken lines showing a sweatshirt in FIG. 1 are included for the purpose of illustrating the invention in use, and form no part of the claimed design. The remaining broken lines shown on the surface of the pocket represent stitching.
